UNITED STATES PATENT OFFICE.

HENRY C. BUCHWALD, OF BALTIMORE, MARYLAND, ASSIGNOR TO THE AUTO TRUCK TRANSFER COMPANY, OF BALTIMORE, MARYLAND, A CORPORATION OF MARYLAND.

DESIGN FOR AN AUTOMOBILE-BODY.

56,736.

Specification for Design.

Patented Dec. 14, 1920.

Application filed July 11, 1919. Serial No. 310,277. Term of patent 3½ years.

To all whom it may concern:

Be it known that I, HENRY C. BUCHWALD, a citizen of the United States, residing at Baltimore, in the State of Maryland, have invented a new, original, and ornamental Design for Automobile-Bodies, of which the following is a specification, reference being had to the accompanying drawing, forming part hereof.

The figure is a perspective view of an automobile body, showing my new design.

I claim—

The ornamental design for an automobile body, as shown.

In testimony whereof, I affix my signature.

HENRY C. BUCHWALD.
